AIR BALANCE FOR PUMPS

Charles M. O'Leary, Houston, Tex.

Continuation of abandoned application Serial No.
196,753, March 18, 1938. This application
February 17, 1940, Serial No. 319,565

16 Claims. (CL 74—589)

This invention relates to an air balance for pumps, especially deep well pumps, and the present application is a continuation, and is filed in the place and stead, of applicant's abandoned application, Serial Number 196,753, which was originally filed March 18, 1938.

In the operation of deep well pumping mechanism it is usual to provide a constantly rotating driving unit which acts through a vertically oscillating walking beam to longitudinally reciprocate the pump rods extending down into a well. It is evident that under such circumstances unequal load conditions will prevail upon the downstroke and the upstroke of the pumping mechanism, thus acting to impose unequal resistance to the driving torque of the prime mover. This is due to the fact that on the upstroke of the pumping mechanism the pump rods are under tension since the walking beam must lift the weight of the rods and that of the column of liquid which is being raised, while on the downstroke the weight of the rods aids in the movement of the pumping mechanism. Of course, during both of the above strokes, the operating crank connected with the walking beam will produce a variable torque drive in its cycle of operation.

Various means have been provided for compensating for these inequalities, such for instance as weights, compressible fluids and incompressible liquids, but in every instance weights and combinations of fluids and liquids as well as liquids alone, practical objections have been found in use. In the present instance the desirable cushioning and counterbalancing action are obtained by the use of a compressible fluid, such as air, used alone.

It is the principal object of the present invention, therefore, to provide a counterbalance means adapted to be operated in conjunction with the walking beam of a pump, and which counterbalance means will automatically act to maintain a constant predetermined pressure of fluid to cushion the downstroke of the well pumping mechanism, and to aid in elevating the pump load on the upstroke, the said structure providing means whereby a desired fluid pressure may be established within the apparatus and automatically maintained, and also means whereby the spacing of the pump rods within the well may be reset.

The present invention contemplates the provision of a combined pneumatic counterbalancing unit which comprises a balancing cylinder and piston, and a storage cylinder communicating

therewith in a manner to automatically control the fluid pressure in both cylinders and to establish and regulate the pressure of fluid in either.

The invention is illustrated, by way of example, in the accompanying drawings, which form a part of this specification, and in which,

Figure 1 is a view in side elevation showing a pumping unit of the type in which the present invention is used and shown, and,

Figure 2 is an enlarged view in central vertical section showing the unit of the present invention.

Referring more particularly to the drawings, 10 indicates a frame structure carrying suitable bearing standards 11 upon which a drive shaft 12 is rotatably supported. The drive shaft carries a pulley or sprocket 13 suitably connected with driving means, and also carries a crank 14. This crank is fitted with a pitman rod 15 pivotally attached at 16 to a walking beam 17. The walking beam is provided with a pivot pin 18 carried at the upper end of a Samson post 19. At the free end of the walking beam a fitting 20 is provided to receive reins 21 of pump rods 22 which reciprocate within a well 23 and operate a pump piston 24.

Disposed at some point between the base 10 and the walking beam 17, and here shown as being positioned between the free end of the walking beam and the base, is an air cushioning unit 25. This unit is fitted adjacent its lower end with horizontally disposed trunnions 26 mounted in a bearing structure 27 and has at its upper end a piston rod 28 pivotally connected at 29 to the walking beam.

Referring particularly to Figure 2 of the drawings, it will be seen that the air cushioning unit 25 comprises the piston rod 28 previously mentioned, which depends from the walking beam and carries a piston 29 at its lower end. This piston reciprocates within a balancing cylinder 30, here shown as being disposed within a closed air cushioning tank 31. The upper end of the balancing cylinder 30 is closed by a head 32 and carries a stuffing gland 33 by which the piston rod 28 is packed.

The lower end of the balancing cylinder is provided with a head 34 to which a pipe 35 is connected. This pipe extends downwardly through the bottom of the tank 31 and is fitted with a manually operable valve 36. Below valve 36 is a pipe 37 carrying a tee 38 to the opposite sides of which are attached return pipes 39. These pipes communicate with the bottom of the

tank 31, and when the valve 36 is opened, they permit the air within the balancing cylinder 38, and beneath the piston 29, to be forced from the cylinder into the tank.

5 The bottom of the cylinder 38 is also fitted with a draw-off pipe 40, which pipe carries a manually controlled bleeder valve 42. Valve 42 is mounted at the end of the pipe 40, and when opened will allow air to be expelled from the bottom of the balancing cylinder alone, assuming that the valve 36 has been previously closed.

10 Due to the fact that the balancing cylinder is fitted at its upper end with a closed head 32, a compression space will be formed therein above the piston 29, as well as beneath said piston. These spaces are indicated at 43 and 44 respectively, and the upper space 43 is fitted with a pipe 45 which leads to a T 46 and conducts air from space 43 to a point outside tank 31. Attached to one end of T 46 is a pipe 48 carrying check valve 49 which may permit an inflow of air from the atmosphere.

15 The opposite side of T 46 is provided with a pipe 50 carrying a check valve 51, in turn connected with a pipe 52 leading to the tank 31. The check valve 51 permits the flow of air to the tank, but not from it.

20 In order to regulate the pressure within the tank 31, a T 60 is placed in the pipe line 45 and is fitted with a pipe 61 which connects with a valve housing 62. This valve housing has a lower opening normally establishing communication between the pipe 61 and the atmosphere through a port 65' in the upper portion of a diaphragm 25 housing 65. A valve element 63 is mounted within the housing 62 and may move to an obstructing position to close the opening into diaphragm housing 65 and cut off the pipe 61 from communication with atmosphere. A diaphragm 64 is 30 mounted in the housing 65 immediately below valve housing 62 and is attached to a valve stem 66 which carries the valve element 63. Fluid pressure from the pipe 52 against the lower surface of the diaphragm 64 holds the valve in a 35 normally open position.

40 A spring 67 compressed above the diaphragm 64 acts to close the valve when a pressure below a determined minimum has been reached in the tank 31 with which pipe 52 communicates. Thus 45 reduced pressure in the tank 31 will automatically act to close the pipe 61 and cause the check valves 49 and 51 to function in pumping air into the tank 31.

45 In operation of the form of the invention here shown and described, the first step is the closing of valves 42 and 36. Valve 63 will be closed. As the piston 29 reciprocates on its downstroke it will draw air from the atmosphere through the check valve 49 and through pipes 48 and 45 to the compression space 43. On the upstroke of the piston 29, this air will be forced through the pipes 45 and 50 to and through the check valve 51, after which this air under compression will be forced through the pipe 52 into the tank 31. 50 This will build up the pressure in the tank 31 and in the compression space 44 of the balancing cylinder, or in the tank only, if valve 36 is closed and valve 42 is opened.

55 When the pressure has reached a definite amount, the pressure-regulated valve 63 will be opened by the force of the pressure against the diaphragm 64, and thereafter the piston 29 will merely displace the air in the compression space 43 by forcing it through pipes 45 and 61 and 60 through the valve housing 62 to the atmosphere.

On the downstroke, air will be drawn inwardly to the upper compression space 43 through the opened valve housing 62.

65 When it is necessary to set the piston 29 in any desired position within the cylinder 38, this may be accomplished by closing valve 36 and permitting air to escape through valve 42 from the compression space 44 of the cylinder. During the operation of the pumping mechanism, on the downstroke the piston 29 will be moved downwardly as 10 the pitman rod 15 forces the driving end of the walking beam 17 upwardly. This downward movement of the piston will be resisted by air under pressure as it is displaced from the compression space 44 through the pipes 35 and 39, into 15 the tank 31, and since the air is a compressible fluid, a pneumatic cushioning action will be produced. This cushioning action will tend to counterbalance the weight of the pump rods as they move downwardly into the well. On the upstroke 20 of the piston, at which time the pump rods and a column of liquid are being lifted within the well, the expansive action of the compressed air within the tank will act upon the balancing piston 29 to aid in lifting the piston and the load 25 of liquid with it.

25 It will thus be seen that by the counterbalancing construction here disclosed it is possible to establish a predetermined counterbalancing and cushioning air pressure within the balancing unit, 30 as an incident to the operation of the pumping mechanism, and to thereafter maintain this air pressure at a predetermined value in direct relationship to the counterbalancing and cushioning 35 action desired.

35 While I have shown the preferred form of my invention as now known to me, it will be understood that various changes may be made in the combination, construction and arrangement of parts, by those skilled in the art without departing from the spirit of the invention as included in the following claims.

40 Having thus fully described my invention, I claim as follows:

45 1. In a well pump of the type including a power actuating walking beam, an air balance comprising a balancing cylinder closed at its opposite ends, a piston reciprocating in the cylinder and forming upper and lower compression spaces therein, a piston rod connected at its lower end 50 with said piston and extending through the upper closed end of the cylinder, means pivotally mounting the lower end of the cylinder upon a fixed base, means pivotally connecting the upper end of the piston rod with the walking beam, 55 a cushioning tank, means freely connecting the lower compression space of the cylinder with said tank, a conduit connecting the upper compression space of the cylinder with the tank, and valve controlled means for said conduit whereby fluid 60 within the upper compression space of the cylinder may be delivered into the cushioning tank when pressure within the latter falls below a predetermined point, and vented to the atmosphere 65 when pressure rises above said point.

70 2. In a well pump of the type including a power actuated walking beam, an air balance comprising a balancing cylinder closed at its opposite ends and mounted for rocking movement, a piston reciprocating in the cylinder and forming upper and lower compression spaces therein, 75 a piston rod connected at its lower end with said piston and extending at its upper end through the upper closed end of the cylinder, means pivotally connecting the upper end of the piston 75

- rod with the walking beam, a cushioning tank, means freely connecting the lower compression space of the cylinder with said tank, a conduit connecting the upper compression space of the cylinder with the tank, valve controlled means for said conduit whereby fluid within the upper compression space of the cylinder may be delivered into the cushioning tank when pressure within the latter falls below a predetermined point, and vented to the atmosphere when pressure rises above said point, and means for permitting air to be drawn into the upper compression space of the cylinder upon the downstroke of the piston.
3. In a well pump of the type including a power actuated walking beam, an air balance comprising a balancing cylinder closed at its opposite ends and mounted for rocking movement, a piston reciprocating in the cylinder and forming upper and lower compression spaces therein, a piston rod connected at its lower end with said piston and extending through the upper closed end of the cylinder, means pivotally connecting the upper end of the piston rod with the walking beam, a cushioning tank, means freely connecting the lower compression space of the cylinder with said tank, valve controlled means for said conduit whereby fluid within the upper compression space of the cylinder may be delivered into the cushioning tank when pressure within the latter falls below a predetermined point, and vented to the atmosphere when pressure rises above said point, and automatic means for permitting air to be drawn into the upper compression space of the cylinder upon the downstroke of the piston.
4. In a well pump of the type including a power actuated walking beam, an air balance comprising a balancing cylinder closed at its opposite ends and mounted for rocking movement, a piston reciprocating in the cylinder and forming upper and lower compression spaces therein, a piston rod connected at its lower end with said piston and extending through the upper closed end of the cylinder, means pivotally connecting the upper end of the piston rod with the walking beam, a cushioning tank, means freely connecting the lower compression space of the cylinder with said tank, a conduit connecting the upper compression space of the cylinder with the tank, valve controlled means for said conduit whereby fluid within the upper compression space of the cylinder may be fed under pressure into the tank, means for permitting air to be drawn into the upper compression space of the cylinder upon the downstroke of the piston, and means controlled by pressure within the tank and acting to automatically vent the air from the upper compression space of the cylinder to the atmosphere whereby to interrupt feed of air from the cylinder to the tank.
5. In a well pump of the type including a power actuated walking beam, an air balance comprising a balancing cylinder closed at its opposite ends and mounted for rocking movement, a piston reciprocating in the cylinder and forming upper and lower compression spaces therein, a piston rod connected at its lower end with said piston and extending through the upper closed end of the cylinder, means pivotally connecting the upper end of the rod with the walking beam, a cushioning tank, means freely connecting the lower compression space of the cylinder with said tank, a conduit connecting the upper compression space of the cylinder with the tank, valve controlled means for said conduit whereby fluid within the upper compression space of the cylinder may be delivered into the cushioning tank when pressure within the latter falls below a predetermined point, and vented to the atmosphere when pressure rises above said point, and means for permitting air to be drawn into the upper compression space of the cylinder upon the downstroke of the piston.
6. In a well pump of the type including a power actuated walking beam, an air balance comprising a balancing cylinder closed at its opposite ends and mounted for rocking movement, a piston reciprocating therein, a piston rod connected therewith, means pivotally mounting the lower end of the cylinder upon a fixed base, means pivotally connecting the upper end of the piston rod with the walking beam, a cushioning tank, means freely connecting the lower compression space of the cylinder with said tank, a conduit connecting the upper compression space of the cylinder with the tank, valve controlled means for said conduit whereby fluid within the upper compression space of the cylinder may be delivered into the tank, and means for manually isolating the lower compression space of the cylinder from the tank.
7. In a well pump of the type involving a power actuated walking beam, an air balance comprising a balancing cylinder closed at its opposite ends and mounted for rocking movement, a piston reciprocating therein, a piston rod connected therewith, means pivotally mounting the lower end of the cylinder upon a fixed base, means pivotally connecting the upper end of the piston rod with the walking beam, a cushioning tank, means freely connecting the lower compression space of the cylinder with said tank, a conduit connecting the upper compression space of the cylinder with the tank, valve controlled means for said conduit whereby fluid within the upper compression space of the cylinder may be delivered into the tank, and means controlled by pressure within the tank for venting the upper compression space of the cylinder to the atmosphere.
8. In a counterbalance for a pumping unit having a walking beam, a balancing cylinder and a pressure tank in a single unit having a pivotal mounting at its lower end, the cylinder being within the tank and closed at both ends, a piston within the cylinder dividing the same into upper and lower compression spaces, a rod extending from the piston through the upper end of the unit and pivotally connected to the walking beam, a pressure conduit between the lower compression space of the cylinder and the tank, and having a portion thereof exteriorly of the tank and provided with a manual cut-off valve, means for feeding air under pressure from the upper compression space of the cylinder into the tank, and means controlled by pressure within the tank for venting the said upper compression space to the atmosphere without loss of pressure from the tank.
9. In a counterbalance for a pumping unit having a walking beam, a balancing cylinder, a pressure tank, the cylinder being closed at its upper end and in communication at its lower end with the tank, a piston in the cylinder dividing the same into upper and lower compression spaces, a

- rod extending from the piston through the upper closed end of the cylinder and connected to the walking beam, means for feeding air under pressure from the upper compression space of the cylinder into the tank, and means controlled by pressure in the tank for venting the said upper compression space of the cylinder to the atmosphere whereby the compressing action may idle without affecting pressure within the tank.
10. In a counterbalance for a pumping unit having a walking beam, a balancing cylinder and a pressure tank in a single unit having a pivotal mounting at its lower end, the cylinder being within the tank with its upper end closed and its lower end in communication with the tank, a piston within the cylinder dividing the same into upper and lower compression spaces, a rod extending from the piston through the upper end of the unit and pivotally connected to the walking beam, means for feeding air under pressure from the upper compression space of the cylinder into the tank, and means controlled by pressure in the tank for venting the said upper compression space of the cylinder to the atmosphere whereby the compressing action may idle without affecting pressure within the tank.
11. In a counterbalance for a pumping unit having a walking beam, a pressure tank, a balancing cylinder normally in communication at one end with said tank, a piston in said cylinder forming a working compression space between the piston and the tank communicating end of the cylinder, means controlled by tank pressure for automatically creating and maintaining predetermined pressure in said tank by piston action during operation of the beam, valve means for cutting off communication between the tank and the said normally communicating end of the cylinder, and a valved connection between said compression space and the atmosphere whereby pressure may be bled from the said compression space when its said communication with the tank is cut off, without affecting tank pressure.
12. In a counterbalance for a pumping unit having a walking beam, a pressure tank, a balancing cylinder normally in communication at one end with said tank, a piston in said cylinder forming a working compression space between the piston and the tank communicating end of the cylinder, and means controlled by tank pressure for automatically creating and maintaining predetermined pressure in said tank by action of said piston during operation of the beam.
13. In a well pump of the type including a power actuated walking beam, an air balance comprising a balancing cylinder closed at its opposite ends and mounted for rocking movement, a piston reciprocating in the cylinder and forming upper and lower compression spaces therein, a piston rod connected at its lower end with said piston and extending through the upper closed end of the cylinder, means pivotally connecting the upper end of the piston rod with the walking beam, a cushioning tank, means freely connecting the lower compression space of the cylinder with said tank, a conduit connecting the upper compression space of the cylinder with the tank, and valve controlled means for said conduit whereby fluid within the upper compression space of the cylinder may be delivered into the cushioning tank when pressure within the latter falls below a predetermined point.
14. In a counterbalance for a pumping unit having a walking beam, a pressure tank, a balancing cylinder normally in communication at one end with said tank, a piston in said cylinder forming a working compression space between the piston and the tank communicating end of the cylinder, and means for automatically creating and maintaining predetermined pressure in said tank by action of said piston during operation of the beam including pressure means in direct communication with the tank for rendering said first named means active and inactive.
15. In a counterbalance for a pumping unit having a walking beam, a balancing cylinder, a pressure tank, the cylinder being closed at its upper end and in communication at its lower end with the tank, a piston in the cylinder dividing the same into upper and lower compression spaces, a rod extending from the piston through the upper closed end of the cylinder and connected to the walking beam, means for feeding air under pressure from the upper compression space of the cylinder into the tank, means for cutting off communication between the lower cylinder space and the tank, and means for venting the lower cylinder space to the atmosphere when cut off from the tank, and thus without reducing tank pressure, whereby the piston may be relieved from tank pressure while compressing within the upper space.
16. In a counterbalance for a pumping unit having a walking beam, a pressure tank, a balancing cylinder closed at its opposite ends, a piston in said cylinder dividing the same into compression spaces at opposite sides of the piston, one of said spaces being normally in open communication with the tank, a rod for actuating the said piston connected to the walking beam, connections for feeding air under pressure from the other cylinder space to the tank, means for cutting off said open communication of the first mentioned cylinder space with the tank, and means for bleeding air from said first mentioned cylinder space and venting the same to atmosphere when so cut off from the tank, without reducing tank pressure, whereby the piston may operate at times without pressure opposition in the said first mentioned space.

CHARLES M. O'LEARY.
